UNITED STATES PATENT OFFICE

2,402,425

EXTRACTION WITH SULPHUR DIOXIDE

Herbert H. Meier, Baytown, Tex., assignor to
Standard Oil Development Company, a corpora-
tion of Delaware

Application September 14, 1942, Serial No. 458,310

3 Claims. (Cl. 196—37)

1

The present invention is directed to the SO₂ extraction of petroleum fractions containing olefins.

The extraction of petroleum fractions with SO₂ is a well known procedure in refinery operations. For the most part, it has been practiced on a commercial basis on virgin distillates. Attempts to apply it to cracked distillates have led to operating difficulties, such as coking of heat exchangers and of other equipment which is heated in the course of the operation to separate SO₂ from the extract and the raffinate. This trouble has been particularly pronounced in operations in which hydroformed naphthas have been employed as the feed stock for the extraction.

It has now been found that these coking troubles hitherto experienced in heated equipment utilized in the handling of mixtures of SO₂ and petroleum fractions containing olefins can be avoided if care is taken to eliminate oxygen other than that combined with the SO₂ from the mixtures. This exclusion of oxygen should be observed at least from the time the petroleum fraction comes into contact with the SO₂ until the two are separated. To this end, the petroleum fraction should be treated just before being mixed with the SO₂ to remove from it any free oxygen or organic peroxides which may be contained in it. In suitable cases this can be done by a stripping operation in which the oxygen is taken off overhead and the organic peroxides are rejected as bottoms. Immediately following this operation, the fraction is blanketed with an inert gas, such as methane, nitrogen, etc., until it is mixed with the SO₂. The system from this point on is ordinarily a closed system, but if there are any accumulators or storage tanks in the system while the petroleum fraction and the SO₂ are in contact with each other, these also must be blanketed with the inert gas or kept under pressure to exclude air or oxygen.

In practice, however, it is preferable to go further and protect the petroleum fraction from contamination with oxygen from the very moment the olefins are formed in the fraction. That is to say, immediately after the cracking, hydro-forming, or other thermal treatment, with or without catalysts, which converts paraffins into olefins, the petroleum fraction is subjected to a distillation to remove any free oxygen that may be present therein and then put in storage under an inert gas until ready for extraction with SO₂. In this way contact between the petroleum fraction and oxygen for a length of time sufficient for the formation of organic peroxides is avoided.

2

The manner in which the present invention is practiced may be better understood from the following detailed description of the accompanying drawing in which the single figure is a front elevation, in diagrammatic form, of one type of apparatus suitable for such practice.

Referring to the drawing in detail, numeral 1 designates a feed line for feeding petroleum distillate into a processing unit 2 which may be a cracking unit or a hydroforming unit or a cyclization unit or any other type of processing unit in which hydrogen is split off from the hydrocarbons. The effluent from this unit is conducted, by line 3, into a distillation column 4, from which the light ends are taken off overhead by line 5. It will be understood that this represents the preferred type of operation in which any oxygen contained in the distillate is taken off overhead with the light ends. The remainder 10 is conducted by line 6 into a second distillation column 7 in which the desired cut for SO₂ extraction is taken off overhead by line 8 and discharged into a storage tank 9, which is supplied with a feed line 10 for inert gas and a pressure relief line 11 containing, if desired, a safety valve. It may be observed that an extremely slow stream of the inert gas may be maintained through the storage tank, since its purpose is merely to exclude oxygen or air. 15

20 The petroleum fraction is then withdrawn from the storage tank through line 12 and introduced into an SO₂ extraction unit 13 into the upper end of which is fed SO₂ through line 14, and from the top of which a raffinate is recovered through line 15 and from the bottom of which an extract 25 is drawn off through line 6. It is in the further treatment of this extract to separate the SO₂ from the hydrocarbons by operations which involve heating steps that coking of the equipment subjected to elevated temperatures has previously 30 experienced. For example, in one such unit the heat exchangers and other heated recovery equipment in which the extract in line 16 was processed coked so rapidly that it was necessary 35 to shut it down after operating for only a 6-day period and to resort to extensive cleaning of it, which involved a 6-day down time. It was found that in most parts of the equipment which were subjected to high temperatures there was a hard coke-like deposit, the removal of which was extremely difficult. After the blanketing operation 40 described above was adopted, the same equipment was operated continuously for a 54-day period, after which a thorough investigation revealed 45 that coke deposition had been negligible. In this 50

particular case, the hydrocarbon feed stock to the extraction unit was a hydroformed naphtha cut boiling between about 200° and 250° F.

The nature and objects of the present invention having been thus described and illustrated, what is claimed as new and useful and is desired to be secured by Letters Patent is:

1. In a method in which a petroleum naphtha is subjected to a thermal conversion and then to extraction with sulphur dioxide, the steps of eliminating from said naphtha immediately after said conversion any organic peroxides and oxygen contained therein, and thereafter excluding oxygen from any atmosphere with which said naphtha may come into contact until the extraction with sulphur dioxide has been completed.

2. In a method in which a petroleum distillate containing olefins is extracted with sulphur dioxide, the steps of preliminarily removing from said distillate any oxygen contained therein, 20

then blanketing said distillate with an inert gas until the extraction has begun, and excluding organic peroxides and oxygen from any atmosphere with which the mixture of distillate and sulphur dioxide comes into contact until the extraction is completed and the sulphur dioxide has been separated from said distillate.

3. In a method in which a petroleum naphtha is subjected to a thermal conversion which produces olefins in the naphtha, and subsequently to an extraction with sulphur dioxide, the steps of removing organic peroxides and oxygen from said naphtha immediately after said conversion, and thereafter blanketing said naphtha, whenever there is a free space above it, with an inert gas until the extraction with sulphur dioxide is completed and the sulphur dioxide is separated from the naphtha.

HERBERT H. MEIER.
